UNITED STATES PATENT OFFICE.

CHARLES REINEKE, OF NEW YORK, N. Y., ASSIGNOR TO THE REINEKE MOTOR CORPORATION, OF NEW YORK, N. Y., A CORPORATION OF DELAWARE.

ENGINE CYLINDER.

Application filed August 16, 1922. Serial No. 657,798.

To all whom it may concern:

Be it known that I, CHARLES REINEKE, a citizen of the United States, residing at New York city, in the county of New York and State of New York, have invented certain new and useful Improvements in Engine Cylinders; and I do hereby declare the following to be a full, clear, and exact description of the invention, such as will enable others skilled in the art to which it appertains to make and use the same.

This invention relates to improvements in cylinders for internal combustion engines, and more particularly to cylinders of the jacketed type.

Before describing the details of construction, it is desirable to review the conditions under which work is accomplished in the cylinder of an internal combustion engine of any type. Whether it is the cylinder of an explosive or expansive engine, the two main factors to contend with are the heat and the strength of the material employed, each, of course, in its own class, according to the fuel and compression used.

The sizes of cylinders constructed in known manners, is limited on account of the heat, as they have to be very thick to withstand the high pressure in larger cylinders. Consequently the cold water has a very slow effect on the internal heat.

Furthermore, to obtain a satisfactory wearing surface for the piston, the inside of the cylinder is usually made of cast iron. The mixture of the cast iron for the best wearing results is not always the most desirable for purposes of strength, and it is for this reason that I propose using the most suitable material for wearing on the interior of the cylinder and the most desirable material for strength exteriorly of said wearing material.

The primary object of the invention is to construct a cylinder having a cast iron liner of a high grade mixture for wearing purposes and to surround this liner with a tube of high tensile strength, so that the thickness of the liner and the tube is kept sufficiently thin for the cooling water to maintain the internal heat within proper limits to facilitate lubricating. To keep the strain on the cast iron liner and its surrounding high tensile strength tube well within its limits, I place an outer tube around the high tensile strength tube and

arrange stays between the inner and outer tubes, so that the outer tube may participate in relieving the strain caused by the pressure on the cast iron liner and inner tube. The outer tube which is spaced from the inner tube and therefore not affected by the internal heat, can be made of extra thickness, and may serve as a water jacket. To strengthen the outer tube, a number of stay rings may be arranged exteriorly of the same and shrunk into place.

This is substantially the broad idea of the present invention and it is to be borne in mind that the various elements are formed of tubes, the innermost tube or liner providing an efficient wearing surface for the piston, and the outermost tubes strengthening the liner and taking the strain from the latter. To demonstrate the advantages of this type of cylinder construction for internal combustion engines, it must be taken into consideration that the tensile strength of rolled steel is about seven times greater than cast iron under ordinary circumstances. Furthermore a steel tube can be inspected throughout and no extra factor of safety has to be allowed, such as is the case with iron castings. Furthermore, there are no internal strains in the steel tube construction as there are in cylinder castings, so that such strains do not have to be considered with the construction provided by the present invention. The greatest advantage, however, is that the heat question can be more favorably handled, as the cylinder walls can be made much thinner, and one can tell exactly how thick each important part is before assembling, in contradistinction to jacketed castings in which it is impossible to inspect the space between the cylinder proper and the jacket. This makes it possible to build a lighter and stronger engine, which facilitates the use of higher compression and consequently a heavier fuel oil. Moreover as the liner and inner tube may be made relatively thin, the spacing between the same and the outer tube will form an efficient means for rapidly heating the water used for cooling, and therefore this water may be converted into steam and the steam utilized to develop power.

As the application of this cylinder construction is as manifold as there are types of engines, at present, no concrete rule can be made for the details, but each type must

be considered separately. Broadly speaking, however, drawn steel tubes for smaller cylinders should be used and rolled steel tubes for larger cylinders, instead of castings for the cylinder housing. These tubes may be straight and clamped together, or the ends of the tubes may be flanged to facilitate connecting the same together. With rolled tubes, tapered and specially formed, electric welding may be employed, and a number of different stay rings, such as internal and external stay rings of various shapes, and fastenings may be used. Screwed and welded stay bolts, solid or hollow, may be employed, and welded or expanded tubes may be used in heads or sides of the cylinder tubes for the purpose of strengthening the surfaces, or to form chambers for ports, valves, or ignition appliances as may be necessary in each separate type.

Therefore, I have in the accompanying drawing shown the use of steel tubes in many types of cylinders. Of course, such tubes may be used with other types of engines, as the broad idea resides in the use of the different materials and the manner in which the cylinder housings are built up.

With the foregoing objects outlined and with other objects in view, which will appear as the description proceeds, the invention consists in the novel features herein-after described in detail, illustrated in the accompanying drawings, and more particularly pointed out in the appended claims.

Referring to the drawings:

Fig. 1 is a longitudinal vertical sectional view of the preferred form of the invention shown applied to an engine cylinder of the opposed piston type of engine;

Fig. 2 is a horizontal sectional view of the same taken on line 2—2 of Fig. 1;

Fig. 3 is a similar view taken on line 3—3 of Fig. 1;

Fig. 4 is a vertical sectional view of what may be said to be the simplest form of the invention;

Fig. 5 is a top plan view of the cylinder shown in Fig. 4;

Fig. 6 is a plan view of one of the stay rings which may be arranged between the inner and outer tubes of various types of the engines illustrated herein;

Fig. 7 is a longitudinal vertical sectional view of a slightly modified form of cylinder particularly adapted for four-cycle engines;

Fig. 8 is a sectional view taken on line 8—8 of Fig. 7;

Fig. 9 is a vertical sectional view of another modification of the four-cycle type of engine;

Fig. 10 is a transverse horizontal sectional view of a cylinder similar to that shown in Fig. 9, but especially modified for two-cycle purposes;

Fig. 11 is a side view of the cylinder shown in Fig. 10;

Fig. 12 is a vertical sectional view of a modified form of cylinder for an engine of the opposed piston type;

Figs. 13 and 14 are sectional views taken on the lines 13—13 and 14—14 respectively, of Fig. 12;

Fig. 15 is a vertical sectional view showing a modified form of cylinder forming part of a motor boat engine of the two-cycle type;

Figs. 16 and 17 are sectional views taken on lines 16—16 and 17—17 respectively, of Fig. 15;

Fig. 18 is a vertical sectional view illustrating the application of the invention to a plural cylinder engine in which the outer tube of high tensile strength material forms the jacket of a plurality of cylinders;

Figs. 19, 20 and 21 are sectional views taken on lines 19—19, 20—20, and 21—21, respectively, of Fig. 18;

Fig. 22 is a detail sectional view taken on line 22—22 of Fig. 20;

Fig. 23 is an end view of the engine cylinders shown in Figs. 18 to 22 inclusive; and

Fig. 24 is a bottom plan view of the latter.

In the embodiment of the invention illustrated in Figs. 1, 2 and 3, 1 designates the cast iron liner provided at its upper end with a flange 2 having bolt holes 3. This liner has near its upper end radially arranged intake ports 4, and below these ports radially arranged exhaust ports 5 are provided. This cast iron liner forms the wearing surface for the piston and the liner is surrounded by an inner tube 6 of high tensile strength material such as steel. In other words, the member 6 is preferably formed from an ordinary piece of steel tubing of the proper length, and it is provided with ports 7 which align with the exhaust ports 5. Surrounding the tube 6 and spaced from the latter to provide a water chamber 8, is a relatively thick steel tube 9 provided at its upper end with brackets 10 secured in position by rings 11. A gasket 12 is placed between the head of the tube 9 and the flange 2 of the liner, and bolts 13 are employed to secure the liner to the upper end of the tube 9 and for clamping the gasket 12 in position. It will be noted that the cast iron liner is not connected to the tube 6 and consequently said liner may be readily expanded and contracted in the inner tube.

In assembling the inner and outer tubes with the liner it is preferred to first rivet or bolt a number of U-shaped rings 14 to the outer tube 9. At the same time a U-shaped ring 15 having base flanges 16 is riveted in position on the inner tube 6 and this ring forms an annular chamber 17 into which the exhaust gases are discharged. Afterwards the inner tube 6 is compressed

into the outer tube 9 from below, and when the tube 6 has been inserted the desired distance, a U-shaped ring 18 is driven into the space between the inner and outer tube from 5 above and riveted into position as shown. It will be understood that all of this takes place before the cast iron liner 1 is placed in position. Subsequently a number of threaded pipes 19 are extended through the 10 outer tube 9 and the periphery of the ring 15 to provide means for discharging the exhaust gases from the chamber 17. These pipes 19 are preferably screwed and expedited into position. After this an upper angle 15 ring 20 is inserted into the chamber 8 from below and this ring is riveted into position as shown. Then a lower angle ring 21 is inserted and riveted into position. Afterwards a channel-shaped ring 22 is inserted 20 and riveted to the inner and outer tubes as well as to a base ring 23, which may be used in securing the cylinder to a crank case or the like.

It may be seen from Fig. 2 that the horizontal portions of the rings 14 are provided with radially disposed recesses 24 for the purpose of permitting water to circulate through the chamber 8, and similar recesses are provided as shown at 25 in the lower 30 rings 20 and 21. The recesses 24 in the upper horizontal portion of each ring 14 are in staggered relation relatively to the recesses in the lower horizontal portion of said ring, so that the studs 26 between the recesses are in staggered arrangement. This arrangement permits the passage of water through the rings without weakening the reinforcing effect of the rings 14 at the points where the recesses 24 are arranged. 40 It will be observed that a number of rings 14 are provided in order to take care of the pressure applied to the inner tube 6 and transfer the strain caused by this pressure to the outer tube 9. Therefore the tube 6 45 may be made relatively thin.

The U-shaped construction of the ring 15 provides a chamber for the exhaust gases which chamber is cooled on three sides by the water passing through the chamber 8, and the water also acts to cool the gases passing through the tubes or pipes 19. Furthermore, as the ring 15 extends entirely around the tube 6, it is not only helpful to the general expansion of the cylinder, but 50 also allows better openings to be placed all around the liner for quick escape of the exhaust gases.

It may be seen that the construction set forth bears some resemblance to a steam boiler construction and that the outer corrugated tube 9 will withstand great pressure, and furthermore this tube may be readily expanded and contracted owing to its corrugated structure. The reason for 60 the corrugated structure may be best un-

derstood by taking the heat question under consideration. There is anywhere from 550° to 1000° heat in the cylinder. This causes the inner tube 6 to become very hot compared with the outer tube 9 and consequently the inner tube will expand lengthwise to a greater extent than the outer tube. To eliminate this initial strain, the outer tube is corrugated so as to stretch easier than the inner tube. As the cylinder construction in Figs. 1 to 3 is for an opposed piston type of engine, the pressure is taken from the piston direct by connecting rods to opposed points on the shaft, thus eliminating this longitudinal stress on the cylinder housing and therefore unaffected the corrugated tube.

It will be understood that the liner 1 is inserted into position after the tubes 6 and 9 have been assembled, and it will also be 65 understood that a port 27 in the tube 9 passes the charge of air to the intake ports 4. The oil injection tube 28 is added to the construction after the various parts have been assembled and it functions to inject the oil 90 into the space between the two opposed pistons.

As before stated, the construction disclosed in Figs. 1 to 3 is preferred by me, and it discloses the broad idea of constructing 95 internal combustion engine cylinders out of already manufactured tubes. By the term "tubes" I mean all kinds of manufactured tubes, solid drawn tubes, welded tubes, and solid rolled tubes. These may range from 100 2 inch cast pipe to 80 inch rolled boiler furnace pipe, for strictly speaking, they are all tubes or pipes. These tubes are used as they have been manufactured and there is no necessity for inside or outside machining. In 105 some cases I may use tubes cut in uniform lengths, and in other cases a flange may be turned over at one or both ends of the tube. In still other cases I press the round tubes flat or oval at certain points for various purposes, but in all cases I employ already manufactured tubes, and not sheet iron tubes, 110 rolled or compressed into different shapes and the sections welded together.

I will now proceed to describe briefly various other types of cylinders for different forms of engines.

In the embodiment of the invention illustrated in Figs. 4 and 5, the inner high tensile strength tube 6^a and the outer high tensile strength tube 9^a are spaced apart at their ends by rings 30 and 31 so as to form a water space 32 between the tubes. In this construction a number of stay rings 33 are placed in the water space and bear on both 125 tubes for the purpose of transmitting the pressure of the inner tube to the outer tube. These rings are also recessed as shown at 34 and the recesses of adjacent rings are arranged out of alignment to provide an 130

eschelon formation, so that the fingers 35 between the recesses are in staggered arrangement to strengthen the structure. One of these stay rings is shown in Fig. 6, and it may be used with various types of cylinders. As shown in Fig. 4, the cast iron liner 1^a preferably extends below the tubes 6^a and 9^a and into the crank case 36.

In the modification shown in Figs. 7 and 8 one end ring 37 is apertured for the passage of bolts 38 and to form water passages 39 leading into the head 40 of the cylinder. The bolts preferably extend through the head and the water space of the cylinder, and are anchored in the base 41. This base may be secured to the crank case by bolts or screws 42. These figures also show the welding of the end ring 37 and the base 41 to the inner and outer tubes 6^b and 9^b. The places of welding are designated 43.

In the construction illustrated in Fig. 9 the ends of the inner tube are flanged outwardly as shown at 44 and 45, the first mentioned flange being apertured at 46 to permit the cool water to travel from the head 47 of the cylinder into the water jacket. The outer tube is also flanged in this case and its lower flange 48 rests on the flange 45, while its upper flange 49 is in alignment with the flange 44. In this construction also the internal stay rings 50 are spot welded in position as shown at 51, and in addition to these strengthening rings, outer stay rings 52 are spot welded at 53 to the outer tube. These last mentioned rings reinforce the outer tube and it is desirable to place the same in staggered relation to the inner rings 50, as shown in the drawings.

The head 47, flange 49, rings 52 and flanges 48 and 45 are provided with orifices to receive the bolts 54 and these bolts have rather long threads so that the lower portions of the same may extend into the crank case, not shown, while their upper ends may receive the nuts 55 employed in securing the head to the flange 49. Fig. 9 also illustrates a desirable construction to be used where a spark plug, oil injection valve, or the like, is connected to the cylinder. As shown in this figure, a short tube 56 is welded at 57 to the inner tube and the outer end of the tube 56 abuts against the outer tube of the cylinder. To permit this the aperture in the outer tube of the cylinder is of less diameter than the outer diameter of the tube 56 and consequently the tube 56 acts as a strengthening element at the point where the apertures extend through the side of the cylinder. The outer end of the tube 56 is welded at 58 to the wall of the aperture formed in the outer tube of the cylinder.

The construction illustrated in Fig. 9 is particularly adapted for 4-cycle engines and the tube 56 is threaded to receive a spark plug, but if the type of cylinder shown in

Fig. 9 is employed in 2-cycle engines then it is desirable to have the exhaust opening extending through the side of the cylinder, and such a construction is illustrated in Figs. 10 and 11. In these figures a cone-shaped exhaust tube 59 is arranged between the inner and outer tubes of the cylinder and is welded in place as shown at 60, the outer end of the tube 59 abutting against the inner surface of the outer tube of the cylinder by reason of the fact that the aperture in the outer tube of the cylinder is of less size than the outer diameter of the tube 59. This outer end of the tube 59 is welded to the outer tube of the cylinder as shown at 61, and ports 62 are arranged in the cast iron liner to permit the passage of the exhaust gases to enter the tube 59. It will be appreciated that the placing of the exhaust passageway in the exhaust side of the cylinder, weakens the construction at the point where the exhaust passage is located, and to eliminate this disadvantage I arrange studs 63 between the inner and outer tubes of the cylinders and weld the outer ends of 60 these studs in place as shown at 64.

The modification shown in Figs. 12 to 14 inclusive is quite similar to that disclosed in Figs. 1 to 3 with certain exceptions, some of which will now be mentioned.

In Figs. 12 to 14, the inner tube 65 of the high tensile strength material is formed in two parts, the upper part designated 66 and the lower part 67. The member 66 is flanged at both ends, as shown at 68 and these flanges are welded to the outer tube 69. The outer tube is enlarged at its lower end into oval shape as shown at 70 and the lower end of this enlargement has a flange 71 resting on the base plate 72. Bolts 73 are welded to the upper end of the outer tube 69 and these bolts hold the liner 74 in place. The liner in this construction has radial ribs 75 which space the upper portion of the same from the upper portion of the tube 69. The exhaust pipes are shown at 76 and it may be seen from Fig. 13 that these exhaust pipes communicate with an annular chamber 77 formed by the flange 68 of the upper section 66 of the inner tube and by flange 78 at the upper end of the lower section 67 of the inner tube. The cast iron liner forms the inner wall of this annular chamber and the outer tube 69 forms the outer wall of said chamber. A jacket tube 79 of oval shape is welded at 80 to the outer tube 69 and at 81 to the flange 71. 82 designates stay rings in the water space and 83 designates stay rings surrounding the outer tube. 84 designates the air intake ports and 85 the exhaust ports. A screw threaded sleeve 86 is provided to receive an oil injection valve.

The 2-cycle motor boat engine shown in Figs. 15, 16 and 17 is also of a construction similar to that just described, that is it in-

cludes a liner 87 of cast iron and an inner tube 88 and an outer tube 89 of high tensile strength material such as steel. The inner and outer tubes have their upper ends contracted to form domes 90 and 91, the dome 90 having a neck or tubular extension 92 extending through the dome 91 and welded to the same at 93. A tap 94 extends into this neck to receive a spark plug or the like. Diametrically opposite sides of the lower portions of the tubes 88 and 89 are flared outwardly as shown at 95 and 96, while diametrically opposite sides at right angles to the last mentioned sides are flattened as shown at 97 and 98 in Fig. 16. It will be noted that the flared portions 95 and 96 abut against one another to close one portion of the lower end of the water space 99 of the cylinder, while the flattened portions 97 and 98 of the tubes are spaced apart, and these spaces are closed by short narrow plates 100, that are welded in position. Bearings 101 and 102 are secured to the flattened portions 97 and 98 by means of bolts 103 and collars 104 surrounding these bolts for spacing purposes. In this form of engine the air is admitted at 105 into the crank case and travels through the pipe 106 into the combustion chamber, from which the exhaust gases are discharged by an exhaust pipe 107. The liner 87 as shown in Fig. 15 has radial ribs 108 at its lower end and screws 109 engage these ribs for holding the liner in position.

In Figs. 18 to 23 inclusive I have shown my cylinder construction applied to an engine having a plurality of cylinders, and in this case the outer high tensile strength material tube 110 forms the jacket for two cylinders, this jacket resting on a spacing member 111, which has notches or recesses to receive the inner tubes 112 of high tensile strength material. It will be seen that the cylinder structure herein includes a single outer tube, two inner tubes 112 and two case iron liners 113. The head plate 114 rests on the tubes 110 and 112 and closes the space between the same so that said space may form a water chamber. Rods 115 have conical enlargements 116 intermediate their ends, which are countersunk in the head plate 114, and these rods extend through the water space of the cylinder structure and are provided at their lower ends with nuts 117. These rods also pass through stay plates 118, the bottom plate 111 and a base plate 119. The stay plates 118, as best shown in Fig. 21, surround both cylinders, that is each plate 118 accommodates two cylinders and is arranged between the inner tubes 112 of these cylinders and the outer tube 110. The plates 118 are apertured at 120 to permit the circulation of water through the cylinder structure.

It will be noted that the outer tube 110 in this form of the invention has its sides

flattened and cross bolts 121 connect these flattened sides and aid in taking up the strain exerted on the same.

The head of this cylinder structure may also include a tube 122 of high tensile strength material, and this tube is recessed to receive upper and lower oval shaped plates 123 and 124. These plates are apertured at various points to receive taps for spark plugs, oil injection valves and the like, and they are also apertured to accommodate intake and exhaust valves 125 and 126, the specific construction of which forms no part of the present invention.

Resting on the upper plate 123 are brackets 127 to support the valve actuating means. It will be noted that the rods 115 extend through the plates 124 and 123 and are provided at their upper ends with nuts 128. The head of the cylinder also forms a water chamber which communicates with the water chamber of the cylinder structure by means of ports 129, shown in Fig. 18. By referring to the various section lines on Figs. 18 to 24 inclusive, the construction of this type of engine may be readily understood.

From the foregoing it is believed that the construction and advantages of the invention may be readily understood, and it is apparent that changes may be made in the details disclosed without departing from the spirit of the invention as expressed in the claims.

What I claim and desire to secure by Letters Patent is:

1. An engine cylinder structure including inner and outer tubes of a material having a tensile strength substantially equal to that of steel and capable of withstanding the pressure created by internal combustion, means permanently securing said tubes together and spacing the same apart, and a tubular liner arranged in the inner tube, bearing against the latter and having properties substantially the same as those of cast iron.

2. An engine cylinder structure including spaced inner and outer tubes of high tensile strength metal, metallic spacing means arranged between the tubes and capable of transferring strains from the inner tube to the outer tube, and a cast metal liner tube arranged in and bearing against the inner tube.

3. An engine cylinder structure as claimed in claim 1 in which the inner tube is of less thickness than the outer tube.

4. An engine structure as claimed in claim 1, in which the spacing means consists of metal rings arranged between the inner and outer tubes and adapted to transfer strains from the inner tube to the outer tube.

5. An engine cylinder structure including spaced inner and outer tubes of high

- 5 tensile strength metal, metallic spacing means arranged between the tubes and capable of transferring strains from the inner tube to the outer tube, and a cast iron liner tube arranged in and bearing against the inner tube.
- 6 An engine cylinder structure including spaced inner and outer steel tubes, metallic spacing means arranged between the tubes and capable of transferring strains from the inner tube to the outer tube, and a cast metal liner tube arranged in and bearing against the inner tube.
- 7 A cylinder for engines including an inner steel tube and an outer steel tube permanently secured together, spacing means between the tubes adapted to transfer strains from the inner tube to the outer tube, and a liner tube of less strength than 15 steel arranged in and bearing against the inner tube.
- 8 An engine cylinder including an inner tube and an outer tube spaced from each other and formed of steel, the inner tube being of less thickness than the outer tube, and a liner tube arranged in the inner tube.
- 9 An engine cylinder including an inner tube and an outer tube spaced from each other and formed of steel, the outer tube 20 being corrugated, and a liner tube arranged in the inner tube.
- 10 An engine cylinder including an inner tube and an outer tube spaced from each other and formed of steel, stay rings arranged between the tubes and provided with 25 apertures to permit the circulation of water between the tubes, and a liner tube arranged in the inner tube.
- 11 A cylinder for engines including a relatively thin inner tube of high tensile strength metal, a relatively thick outer tube of high tensile strength metal surrounding the inner tube and spaced from the latter, and metal stay rings arranged between the 30 tubes and bearing against both tubes for transferring strains exerted on the inner tube to the outer tube.
- 12 A cylinder as claimed in claim 11 including a channel-shaped ring connected to the inner tube and forming an exhaust gas 50 passageway for the cylinder.
- 13 A cylinder as claimed in claim 11 including a channel-shaped ring connected to the inner tube and forming an exhaust gas passageway, and short tubes connecting the 55 bottom of said channel-shaped ring to the outer tube.
- 14 A cylinder as claimed in claim 11 including a cast iron liner arranged in the inner tube.
- 15 A cylinder as claimed in claim 11 including a cast iron liner arranged in the inner tube and having one of its ends connected to one of said tubes, the other end of said liner being unsecured and free to expand 60 and contract.
- 16 A cylinder including a relatively thin tube of high tensile strength material, a relatively thick outer tube surrounding the inner tube and provided with corrugations, 70 stay rings arranged between the tubes and adapted to transfer strains from the inner tube to the outer tube, and a cast iron liner arranged in the inner tube.
- 17 An engine cylinder structure including spaced inner and outer tubes formed of steel, metallic spacing means arranged between the tubes and capable of transferring strains from the inner tube to the outer tube, and a cast iron liner tube arranged in 75 the inner tube and bearing against the inner tube.
- 18 In an internal combustion engine, an inner tube and an outer tube formed of high tensile strength metal and each consisting of a length of ordinary high tensile strength 80 metal piping, spacing means arranged between the tubes and capable of transferring strains from the inner to the outer tube, and a cast iron liner tube arranged in the inner tube and bearing uniformly against the latter for transferring strains caused by internal combustion, to the inner tube.

In testimony whereof I affix my signature.
CHARLES REINEKE.
